UNITED STATES PATENT OFFICE.

ROBERT E. PECK, OF CINCINNATI, OHIO, ASSIGNOR TO THE PECK, HANNAFORD & PECK COMPANY, OF CINCINNATI, OHIO, A CORPORATION OF OHIO.

VENTILATOR CANOPY.

Application filed May 13, 1926. Serial No. 108,938.

My invention relates to canopies for covering or enclosing purposes, and is particularly directed to canopies adapted to remove vapors and fumes from a source thereof such as a laundry machine. The improvement is more particularly directed to an apparatus as a part of the canopy for easily and quickly raising the sides of the canopy from their operative or vapor confining and venting position about the machine to a position clear of the machine for permitting of access to the working parts thereof.

The invention is applicable to a canopy especially adapted for use in conjunction with a laundry machine of the flat work ironer type, this canopy being described and claimed in applicant's Patent No. 1,632,381. The structure disclosed in the applicant's issued patent is designed to overcome the problems arising from the excess of heat and vapors which would otherwise be discharged into the air of the laundry work rooms, thus hindering the proper ventilation of said work rooms and rendering the air of said rooms unfit for the use of the operators, and also to overcome the problem of condensation of the said vapors upon the walls and windows and the dripping of water upon the ironing machinery and the work as it is fed through the machine.

Since the present invention is combined with a considerable portion of the mechanism of applicant's patent it is believed a brief summarized statement of the general structure will aid in understanding the objects of the present invention. The canopy generally consists of a stationary top either hung from the ceiling or supported on the machine itself, and sides or hood portion hung from the top and extending down far enough to enclose the space above the machine. All heated and moisture laden air arising from the machine is trapped in the enclosed space and carried to the outside by means of a suction device mounted on the top. The sides are made transparent in order that the interior of the canopy and moving work passing through the mechanism of the machine may be visible, for detecting any trouble that might arise during operation. In the event that trouble does arise or that the mechanism of the machine requires attention the sides of the canopy are made vertically movable in connection with the top which remains stationary, and a device is provided for hoist-

ing and lowering the sides to provide access to the space above the machine and ordinarily enclosed by the said canopy.

A canopy of sufficient dimensions to cover the larger size of machines for an efficient trapping of the heated and moisture laden air arising from the machine is a heavy device and the movable sides are difficult to handle in the raising and lowering operations. The present invention for this reason discloses a novel structure for performing these operations mechanically by means of a power driven apparatus.

Therefore, an object of this invention is to provide a power driven hoisting device which has its power source in common with a suction device for drawing off the trapped heated and moisture laden air within the canopy, the said hoisting device being manually controlled for selective operations in either a raising or lowering movement of the sides or for an intermittent movement thereof, and this movement being automatically limited.

Another object is to provide a simple and efficient mounting of the sides about the stationary top and suitable connection between the hoisting apparatus and the sides, to provide for a smooth and uniform raising or lowering of the sides and to provide a hoisting apparatus compactly mounted on the stationary top.

Another object is to provide a stationary top for the canopy made up of sections hung in a framework, the suction device and hoisting apparatus mounted in a single section thus facilitating assembly of the canopy organization.

Another object is to provide a power hoist for a canopy which is manually controlled from a point easily accessible to the operator, and in which the power is transmitted from the power source to a lead screw mechanism for imparting a comparatively slow raising or lowering movement to the canopy sides, the movement under instant manual control at any point, and positively limited in either direction of movement.

Another object is to provide lighting fixtures for illuminating the interior of the canopy, the fixtures being slidable into and supported at the base of vertical tubes formed within the top structure, and the fixtures being easily removable merely by sliding them upwardly from the tubes.

Other objects, features, and certain advan-

ages will be disclosed in the description of the drawings in which:

Figure 1 is a top plan view of the canopy.

Figure 2 is a sectional view taken on line 5 2-2, Figure 1, showing the suction device for drawing the vapors from the canopy, the power hoist device and hoist control mechanism.

Figure 3 is a sectional view taken on line 10 3-3, Figure 1, further illustrating the hoisting apparatus and the lighting apparatus mounted in the top sections for illuminating the interior of the canopy.

Figure 4 is a sectional view taken on line 15 4-4, Figure 1, detailing the metal structure of the top and sides and their relation when the sides are down for providing a closure.

Figure 5 is a detail plan view of one of the corners of the canopy illustrating the mounting of the hoisting cables at the corners and the rollers engaging the corners of the side frame for maintaining the side frame in a proper relation to the top.

Figure 6 is a diagrammatic view of the 25 canopy in position over a machine for exhausting the vapors therefrom and showing the hoist control ropes extending to the front of the machine.

The top of the device comprises a main 30 skeleton top frame consisting of the angle members 1 secured at their corners by angle pieces 2 to form a rectangular framework, this framework providing the main supporting frame for the various sections mounted thereon. The framework is shown supported on the machine 3 (see Fig. 6) by means of standards 4 shown in dotted lines. The framework may instead be hung from the ceiling but the former method is the more rigid. The various sections are seated and supported within the angles 1 and as illustrated there is a central section 5 carrying the hoisting and suction apparatus, sections 6 one at each side of the central section each carrying lighting means for the canopy, and the filler sections 7 at the ends made of proper width to fill out the canopy length. It can readily be seen that the size of any of the sections is purely arbitrary and depends on the dimensions of the machine to which the canopy is fitted. These sections and the framework make up the stationary top of the canopy from which the side or hood frame 8 is hung.

The hood frame comprises the sides 9 and the ends 10 preferably fabricated of sheet metal and glass and presenting from the outside a neat paneled box-like structure. The sides and ends are secured together at the corners by means of angle irons 11 to form a rectangular structure open at the top and bottom and of slightly larger dimension in plan view than the rectangular top framework. This permits a telescoping of the hood frame and the stationary top with a slight

clearance at all sides for permitting free movement of the hood frame thereon. The sides 9 and ends 10 of the hood frame are formed of two sheets of metal spaced slightly apart and lapped over at the corners and edges to form a hollow space between the sheets. This construction provides rigidity and the hollow space serves as a dead air or insulating space. Openings 13 are provided in the sides and ends as windows, and window panes 14 are secured therein. Describing an upper portion of the side walls (see Figure 4), the outer sheet is bent to form a top wall 15 and side wall 16 and the lower end is turned upon itself to receive the lower end 18 of the inner sheet, and to form a flange 17, the inner sheet then being turned inward to form a space between the two sheets and forming the inner side wall 19 extending up to be secured to the under side of the top wall 15. The window glass edge is secured against this flange 17 by means of metallic strips 21 suitably secured to the flange. Secured to the tops 15 of the hood walls are hook-like flanges 22 which extend around the entire upper edge 90 of the frame and overhang the upper edge of the angle 1 of the framework as a closure and support means when the hood frame is lowered into operative position.

In order that the hood frame may be spaced evenly from the frame work of the top, and that it may move with less friction thereon, roller devices 23 (see Fig. 5) are provided at each corner of the canopy. The roller devices 23 consist of studs 24 secured in the corner angles 2 of the top frame work and extending outward therefrom to bisect the corner angles 11 of the hood frame at their inner side. The studs 24 have forked ends 25 carrying rollers 26 vertically mounted for contacting or bearing against the bisected corners of the angles 11. Nuts 27 are provided engaging the threaded inner ends of the studs at opposite sides of the angle for adjustably mounting the roller devices 23 to secure an equal spacing between top frame and hood frame at all sides of the canopy.

The stationary top and hood frame together form a rectangular structure open at the bottom, the bottom serving as the intake opening for the canopy when mounted over the machine. The top is mounted on the before mentioned standards 4, a sufficient distance to provide for access to the mechanism of the machine being vented when the sides are drawn up. The sides of the hood frame when in their lower position extend to the machine, and the bottoms thereof may be fitted to the exact shape of the machine frame. The circulation for the ventilating system is 120 through the feed and discharge ends 28, 29, respectively of the machine from which the vapors are being exhausted.

The discharge duct for the vapors is through the top and the suction element for 130

creating the vapor exhausting circulation is inserted in the vent. The central section 5 having thus mechanism mounted therein, is rectangular and box-like in outline, and is 5 formed of metal sheets suitably secured together. An opening 30 is provided in the top 31 of this section and at one end, and a plate 32 is secured thereto. Secured to the upper side of this base plate 32 is an electric 10 motor 33 having a shaft 34 which extends through the plate and has the fan 35 hung thereon on the inside of the section. The discharge duct has its opening 36 from the floor 37 of the section. A funnel shaped 15 element 38 surrounds the opening 36 and extends upwardly to constrict the vapor passage in order to direct the vapor into the blades of the fan. The duct is made up of vertical walls 39 encircling the fan and secured to the floor and top of the section. The vertical walls 39 (see Fig. 1) are built close to the fan at one side and made to flare out at the other side in the direction of fan rotation, that is to say, the duct wall surrounding 20 the fan is circular in plan view but not concentric with the fan shaft center. The fan rotation for the particular structure is anti-clockwise as viewed in top plan view. The flaring wall provides a vapor discharge 25 or release space at the side of the fan, this passage merging into a channel 40 extending longitudinally of the section and curving upward to form a square vertical casing 41 extending through the top of the section. The channel walls and section body are secured together by any suitable fastening 30 means.

In the type of fan shown, the suction which 40 draws the vapors through the opening 36 into the fan, is created by the rapid discharge of vapor from the fan interior due to the speed of rotation, this air being discharged horizontally through the channel 40 and then upwards through the vertical casing (as indicated by the arrows in Fig. 2). Pipe sections 42 are secured to the vertical casing 41 to form a discharge line to the outside air.

The motor used herein is designed for vertical use and has a broad supporting base 50 which as stated before is rigidly secured to the base plate 32. The motor shaft 34 extends through the hub at top of the motor. The drive for the hoisting apparatus is taken from the upper end of the motor shaft and 55 constitutes mechanism adapted to be engaged with this rotating fan driving shaft 34. Since the ventilating mechanism is in operation at all times during the use of the machine from which the vapors are being exhausted, the operators of the machine have a power hoist which can be started merely by a simple manual shift, which connects this motor shaft to the hoisting mechanism (hereinafter described).

60 The mechanism for transmitting this mo-

tor power to the sides for a raising or lowering operation embodies means which automatically limits the amount of movement, preventing any misuse of the hoist and provides an even pull at each corner of the sides 70 or hood portion of the canopy, so that there is no twisting of the hood frame.

A bracket 43 is secured to the hub 44 at the top of the motor by means of screws, and the shaft 34 extends through this bracket. 75 Keyed to the extending portion of the shaft 34 is a friction clutch element 45, having a beveled upper face 45^a. A horizontal shaft 46 is rotatably and slidably mounted in bearings 47 secured to the bracket 43, there being 80 two of these bearings, one at each side of the motor shaft and equally spaced therefrom. The bracket 43 has the arms 48 extending upwardly and the horizontal end portions 49 on which the bearings 47 are secured. 85

Secured to the shaft 46 so as to impart motion thereto, are two friction clutch members 50 as companion members to the driving member 45. Bevel edges are provided on the clutch members 50, these edges being opposingly related and facing inwardly toward the driving clutch member 45 and adapted to be alternatively frictionally engaged or disengaged from the bevel edge 45^a of the driving member. The clutch members are made 90 up of metal portions and rubber composition portions, the bevels being formed of the rubber composition for creating greater friction and a more positive grip on the bevel edge 45^a of the driving member when engaged therewith. 100

The shaft 46 is translatable in its bearings and clearance is provided between the clutch members 50 and the bearings 47. The clutch members 50 are sufficiently spaced apart to permit disengagement of the members from the driving clutch member when the shaft is translated for a clutch control. On the outer end of the shaft and beyond the bearing thereof, shift collars 52 are secured and 110 spaced apart, the end of a pivot shift lever 53 being inserted between the collars. A pivot bracket 54 extends out from the main bracket 43 and to this the lever 53 is fulcrumed. The shift lever extends downwardly and is pivotally secured to an automatically or manually shifted rod 55 mounted on the top of the section. Translation of this lower shift rod produces translation of the upper power shaft 46 and the desired clutching and unclutching operations. 115

A pulley 56 is secured to the opposite end of the shaft 46 and conveys the drive by means of a belt 57 downwardly to a pulley 58 secured on the end of a lead screw 59. The pulley 56 is provided with a wider face than the belt width to allow for the shifting of the belt thereon when the shaft 46 is translated. The lead screw extends horizontally across the section and is mounted in bearings on a frame 60. 130

The shift rod 55 is translatable mounted in the frame 60 parallel to and at the side of the lead screw 59. A slide block 61 engages the threads of the lead screw and is translated 5 by means of the rotation of the lead screw. The block is slidably mounted on the longitudinal bearing surfaces 62 of the frame 60. The contact of the lower edges of the block with the bearing surfaces 62 prevents rotation 10 of the block with the lead screw, this imparting the translating movement to the block.

A pair of hoisting cables 63, 64, for raising the hood frame are secured to the slide block 61 and engage over respective pulleys 15 65, 66, secured on the edge of the section. The cables turn on the pulleys and extend downwardly at the end of the section or at the side of the entire top structure and engage about the respective pulleys 67, 68, secured 20 on the section supporting web of the side angles 1. From these pulleys 67 and 68 the cables extend in opposite directions, that is, toward the ends of the top structure and along the side angles 1.

25 The various sections at the top are of such length as to rest somewhat on the edges of the angles and to leave a space 69 around all sides of the sections. That is to say, the outer ends and sides of the various sections 30 are of sufficient dimension to extend over the supporting web of the angles 1 a sufficient distance for support, this leaving the before mentioned space 69. The space between the sections and the upwardly extending web of 35 the side angles provides a clearance space for the mounting of the cables and the pulleys incident to the directing of the cables.

Inasmuch as the manner of directing the cables to their connection on the hood frame 40 is identical for either end of the canopy, the description thereof will be confined to the structure at one end only. The cable 63 extends longitudinally of the top and along the inside of the angle 1 and is secured to an 45 equalizer plate 70. Hoisting cables 71, 72, extend from the equalizer plate to the respective corners of the canopy organization in the following manner. One of these cables 71 is engaged over a pulley 73 secured to the 50 side angles 1 on the same side of the top frame as that toward which the cables 63, 64, extend from the slide block. The cable 71 turns downwardly from this pulley 73 through an 55 opening in the corner of the skeleton frame and within the corner of the hood frame, and is secured to a cross piece 75 fastened in the corner of the hood frame and at the base thereof. The other cable 72 is turned in a horizontal plane at the corner in which the 60 pulley 73 is located by means of its engagement with the pulley 76 secured to the side of the end angle 1. The cable 72 then extends through the end space 69 to a pulley 77 and is connected to the hood frame at the adjacent 65 corner in the same manner as the cable 71 is

secured to its respective hood frame corner. Thus from a common source of motion, namely, the slide block, pull is transmitted equally and vertically to all four corners of the hood frame.

70

A manual control is provided for the hoisting apparatus and has its connection to the mechanism previously described in the following manner:

Intermediate of the fulcrum point of the 75 lever 53 and its connection to the shift rod 55 there is secured an end 80 of the connecting lever 81. The lever 81 extends downwardly and has its lower end fastened to a shift lever 81^a at a point intermediate the 80 ends of the lever 81^a. The lever 81^a is pivoted at one end to the lead screw frame 60 and has its movable end 82 extended horizontally across the section.

A pair of cables 83, 84, are attached to 85 the free end of the shift rod. The cable 83 extends about a pulley 85 secured on the section top and upwardly to the ceiling 86. (See Fig. 6.) Here the cable 84 is run through a pulley 87 and depends therefrom. The other cable 83 extends in an opposite direction from the first and then about a pulley 88 and back to a pulley 89, at the side of pulley 85 thence upwardly and over another pulley on the ceiling in the same manner as 95 the first cable. The cables depend downwardly to a point easily accessible to the operator of the machine being vented, preferably at the feeding end and have rings attached to their respective ends. This arrangement provides for a controlling movement of the shift lever 81 in either direction.

100

Automatic control of the power operation of the hoist is provided for operation independent of the manual control. Dogs, 105 respectively termed upper limit dog 90 and lower limit dog 91 are secured on the shift rod 55 and have lugs thereon extending toward the lead screw and into the path of the slide block 61. The dogs are placed on the shift 110 rod toward the ends thereof so that the slide block actuates the shift rod, by contacting these dogs after it has traversed approximately the length of the lead screw in either direction.

115

It is readily apparent that these dogs can be set at the exact position for automatically disengaging the friction members at the proper moment, that is, when the hood frame is sufficiently raised or lowered.

120

In order that the purpose of the particular structure will be made clear, a complete hoisting operation will be explained. The canopy as illustrated in the drawings is in its lowered or ventilative position and remains thus during the operation of the machine being vented. When the operator desires access to the rolls of the flat work ironer or to any of the mechanism thereof, he pulls the control rope 84 for a power raising of the 125 130

hood frame. This swings the shift lever 81^a and the motion is imparted to the lever 53 through connecting lever 81. The movement of the lever 53 translates the shift rod 55 and thus moves the upper limit dog 90 thereon into position for actuation by the slide block. Movement is also imparted to the power shaft 46 through the shift collars 52, this engaging the proper clutch member 10 50 with the driving clutch member 45 for a driving motion of the shaft 46. This motion is transmitted to the lead screw 59 by the belt 57 whereupon the slide block is drawn towards the pulley end of the lead screw, this 15 drawing the hoisting cables and raising the hood frame.

As the slide block 61 traverses the frame 60 it strikes the dog 90 and translates the rod 55 sufficiently to impart a clutch disengaging or 20 neutralizing movement to the power shaft 46. Immediately upon this action the block stops and the hood frame is at its upper limit and is in a position shown in dot-and-dash lines, Figure 6.

25 For a lowering of the hood the operator pulls the control cable 83 and the motions of the various levers are thereupon in a reverse direction from that in the described raising operation, the cutting out of the power taking 30 place when the slide block contacts the lower limit dog 91, (see Fig. 1). The lower limit dog is arranged to cut out the lowering power motion slightly after or simultaneously with the contacting of the flanges 22 of the hood 35 frame with the upper edge of the angle members 1 of the top frame. This makes a tight closure with no chance for vapors to escape between the top and hood frame.

The sections 6 are fabricated of metal to the 40 form of a rectangular box-like structure of the same length as the central section 5 and of a sufficient height and width to house the lighting fixtures 93. As shown, there are two 45 of the fixtures 93 in each section. Vertical tubes 94 are inserted in the sections, these tubes being open at both ends and secured by flanges in apertures in the top and bottom of the sections. The flanges 95 at the lower ends 50 of the tubes are turned inward to form circular ledges for the support of the circular lighting fixtures. Any type of lighting fixture 55 may be used so that it has a sufficiently large reflecting body to spread the light throughout the canopy interior, the tubes being made of the proper diameter to snugly house the fixtures therein.

The filler sections 7 are the same height and 60 length as the sections 6 but their width is varied to fill out the top length of the particular canopy. The sections 7 are also rec-

tangular in shape and fabricated of metal. The tops thereof are formed of corrugated metal 96 to provide strength to the sections so that they will not collapse in the event that considerable weight is put upon them. The 65 various sections can be secured to the angle members by any suitable means.

The entire canopy top organization is thus built up of units each serving a respective purpose and the central section completely 70 containing the hoist and suction apparatus. Ease in setting up and rigidity in the finished product are thus advantages of a structure which is positive in operation and has distinct merit in its practical commercial utility. It 75 is intended that the covering device herein disclosed illustrates only one use to which the apparatus can be adapted. Whenever there is covering to be done whether the purpose is to draw off fumes, vapors, etc., or to provide 80 a sealed closure for housing objects during processes where an enclosure of this nature is desirable, the device is readily adaptable since it provides for ease in the removal of the cover from about the thing enclosed. 85

Having described my invention, I claim:

1. A hoisting mechanism, comprising, a rectangular frame, a platform surrounded by said frame, said frame telescoping on said platform, a power source, a slide block, a bearing frame having longitudinal slideways for said slide block, a screw journaled in said frame parallel to the slideways, a power control lever, a power control rod slidably journaled in said frame parallel to said slideways and connected to said power control lever, stops provided at opposite ends of said rod and alternately engageable by the block in its movement along the slideways, and cables connecting the block and the respective corners of the rectangular frame, whereby the frame is raised and lowered by movement of the block. 95

2. In a mechanism for hoisting, a platform, a rectangular frame telescopically 105 mounted on said platform, a feed screw journaled on said platform, a power source for driving said screw, a block traversed by said screw, cables connected to the block and to the corners of the rectangular frame, a clutch 110 between said power source and said lead screw, a clutch control lever, and a trip rod connected to said control lever, said trip rod having portions engageable by said block at the upper and lower limits of movement of 115 said frame whereby the clutch is automatically disengaged.

In witness whereof, I hereunto subscribe my name.

ROBT. E. PECK.
